KENDRICK & DAVIS, OF LEBANON, NEW HAMPSHIRE, A FIRM.

ELECTRIC INDUCTION-BATTERY.

No. 840,728.

Specification of Letters Patent.

Patented Jan. 8, 1907.

Application filed November 15, 1906. Serial No. 343,592.

To all whom it may concern:

Be it known that I, HALLE E. WILLIS, of Lebanon, in the county of Grafton and State of New Hampshire, have invented certain 5 new and useful Improvements in Electric Induction-Batteries, of which the following is a specification.

This invention relates to electric batteries for therapeutic use, and has for its first object to improve the construction of such batteries so that the noise produced by the rapid vibrations of the circuit-breaker may be diminished and reduced to the minimum.

Another object is to provide a more compact and accessible arrangement for mounting the battery-cell which generates the current.

In carrying out these objects I mount the circuit breaker or interrupter so that the vibrations transmitted therefrom to the supporting-base of the battery, which acts as a resonator, will be absorbed and their intensity reduced to the minimum, and provide an improved holder for the current-generator, 25 all as described and claimed in the following specification and illustrated in the drawings.

Figure 1 represents a plan view of the complete battery. Fig. 2 represents an elevation of the same. Fig. 3 represents, on an enlarged scale, a section of the circuit-breaker, showing the manner in which it is connected with the induction-coil. Fig. 4 represents an end elevation of the same. Fig. 5 represents a view similar to Fig. 3, showing a 35 modification of the means for supporting the circuit-breaker. Fig. 6 represents an end elevation of the modification shown in Fig. 5.

The same reference characters indicate the same parts in all the figures.

In the drawings, 1 represents a base to which is secured the induction-coil 2 of the battery. This is constructed in the usual manner with primary and secondary coils and a core 3. The current is derived from a 45 battery 4, which consists of a cell held by supports 5 and 6. One of these supports is connected with one end of the primary coil of the induction device, while the other support is connected with a post 7, having an 50 adjustable terminal 8. The circuit inter-

rupter or breaker is represented by 9 and is shown in Figs. 4 to 6 as being mounted to vibrate in the usual manner between the core 3 and terminal 8.

It is well known that the rapid vibrations of the circuit-breaker produce a note which is very insistent and annoying. It is particularly objectionable in a therapeutical device, as the nerves of invalids are frequently in an abnormally sensitive condition, so that they are more strongly affected and disturbed to a greater degree by continued sounds of this character. Usually the circuit-breakers in such devices are mounted upon springs which yield only in one line to permit the circuit-breakers making their necessary vibrations; but such springs are unyielding in any other direction and are rigidly secured either to the induction-coil or to the base, by which the latter is supported. Thereby the sound-vibrations set up in the circuit-breaker and in the spring are directly transmitted and carried to the base of the apparatus, which, being usually a flat board, is a powerful resonator which greatly intensifies the sound produced by these vibrations.

It is the aim of my invention to eliminate the reinforcement of this sound by the resonant base, so that the only tone produced will be that caused by the circuit-breaker itself and will therefore be of much less intensity than when reinforced by the vibrations of the base.

I accomplish this by securing the circuit-breaker 9 upon the end of a spring 10, which is formed of as many spiral coils as can conveniently be employed, and the opposite end of which is secured to a holder 11. The latter is connected electrically to and supported by the surrounding flange 12 of the induction-coil, the latter being connected with one end of the primary winding. Thus the circuit-breaker is supported yieldingly at the end of a long length of flexible spring, of which portions extend parallel to the base and permit the circuit-breaker to have a motion yieldingly up and down and in any direction whatever in addition to the back-and-forth movement between the core 3 and terminal 8.

I have found that when the circuit-breaker is thus mounted the noise produced is very 95 100

- slight and is very much less in amount and insistence than that produced when the circuit-breaker is mounted upon a flat rigidly-held spring of the usual character. I attribute this result to the fact that the flexibility of the spring 10 causes the sound-producing vibrations to be absorbed before they can be transmitted through the holder 11 to the base 1.
10. In the form shown in Fig. 3 the holder 11 is connected with the flange 12 by a number of arms 13, which are resilient and yield laterally but not in the direction of their lengths. With this form of the device the vibrations 15 must be absorbed wholly by the spring 10. In Figs. 5 and 6, however, I provide an additional sound-absorbing contrivance which consists of the springs 14, used as substitutes for the arms 13 in connecting the holder 11 to the flange 12 of the coil. As may be readily seen, these springs support the holder itself yieldingly, and so act still further to absorb and diminish the intensity of the vibrations transmitted from the circuit-breaker.
20. As previously stated, the current-generating device consists of a battery-cell 4. In order that this may be accessible, I inclose it removably in a casing 15, which has a detachable cover 16 at one end. Mounted in the 25 cover 16 is a stud 17, insulated therefrom by a bushing 18 and having on its outer end a clamp-nut 19. This stud is connected with the electrode 20 of the battery-cell by a wire 21. In the opposite end of the casing is fixed 30 a stud 22, having a lamp-nut 23. This stud is connected with the other electrode through the body of the casing 15 and the outer shell of the cell 4, which makes contact with the casing. These studs 17 and 22 are set into 35 notches in the ends of the supports 5 and 6 and are clamped therein by the nuts 19 and 23. Thus the cell is not only supported by the members 5 and 6, but the latter serve as leads to conduct the current therefrom to the 40 coil. As they rise from the base the cell is thereby supported in a position where it can be easily removed when it becomes exhausted and needs renewing, and the casing enables the cell to be protected from injury. This 45 50 construction of the casing and cell also enables cells of any size to be mounted in the battery, for the casing is large enough to take the largest cell of the required sort which makes a close fit therein, and of course cells of smaller size may be inserted. The metallic shell of the cell resting against the casing makes a contact therewith and with the stud 22, while the flexible connection 21 enables the cell, whatever its size or form of carbon 55 60 may be, to be connected with the stud 17.
- I claim—
1. In an induction-battery, a circuit-interrupter mounted to yield in all directions.
  2. In an induction-battery, a circuit-interrupter mounted yieldingly with respect to the supporting-base of the battery so as to be capable of moving toward and from, as well as parallel to said base.
  3. In an induction-battery, a circuit-interrupter, mounted to yield relatively to the supporting-base of the battery so that its vibrations may be largely absorbed before reaching the base, whereby the sound produced is diminished.
  4. In combination with an induction-coil, a circuit-breaker; and a spring holding the circuit-breaker, having a portion extending transversely of the supporting-base of the coil, whereby it may yield relatively to said base to absorb and diminish the sound-vibrations transmitted from the circuit-breaker through the spring to the base.
  5. In combination with an induction-battery, a circuit-breaker, and a coiled spring in electrical connection with the primary coil of the battery and by which the circuit-breaker is supported with capability of yielding in all directions; the sound-producing vibrations of the circuit-breaker transmitted through the spring to the supporting-base of the battery being absorbed by the flexibility of the spring and diminished in intensity.
  6. In an induction-battery, a holder supported in electrical connection with the primary coil, adjacent the core of the battery; a spiral spring attached at one end to the holder, making electrical contact therewith; and a circuit-breaker connected to the other end of the spring and yieldingly supported thereby.
  7. In an induction-battery, a holder; a plurality of springs supporting said holder yieldingly adjacent the core of the battery and making electrical connection between the primary coil thereof and the holder; a spiral spring attached at one end to the holder, making electrical contact therewith, and a circuit-breaker connected to the other end of the spring and yieldingly supported thereby.
  8. An electrical induction-battery, including an induction-coil, a battery-cell, and supports connected electrically with the coil, by which said cell is removably held and with which the terminals of the same make electrical contact.
  9. An electrical induction-battery, including an induction-coil; supports for a battery-cell in electrical connection with the coil; a cell-casing having at one end a fixed stud adapted to engage one of said supports; a cover for the casing having an insulated stud adapted to engage the other support; and a battery-cell contained in said casing having one of its electrodes making electrical contact therewith, and its other electrode connected with the stud in the casing-cover.
  10. In an induction-battery, a current-

generating cell; a casing in which said cell is removably contained and with which it makes electrical contact; a stud fixed to said casing; a cover for the casing; a stud secured therein and insulated therefrom; a connection from the other cell-electrode with said stud; supports for the casing with which the studs thereof are detachably engaged and

make electrical contacts; and an induction-coil in circuit with said cell-supports. ¹⁰

In testimony whereof I have affixed my signature in presence of two witnesses.

HALLE E. WILLIS.
